LOCKET

Filed June 21, 1923

Inventor

John Costello
By Joseph A. Miller

Attorney

UNITED STATES PATENT OFFICE.

JOHN COSTELLO, OF PROVIDENCE, RHODE ISLAND, ASSIGNOR OF ONE-HALF TO OSIER MANUFACTURING COMPANY, OF PROVIDENCE, RHODE ISLAND.

LOCKET.

Application filed June 21, 1923. Serial No. 646,847.

To all whom it may concern:

Be it known that I, JOHN COSTELLO, a citizen of the United States, residing at Providence, in the county of Providence and 5 State of Rhode Island, have invented new and useful Improvements in a Locket, of which the following is a specification.

This invention relates to certain new and useful improvements in a locket and it has 10 for its primary object to produce such an article of jewelry wherein the hinge is practically concealed, or is flush with the outer surface of the locket.

The invention further relates to a novel 15 hinge construction wherein the internal flange of the body forms a part thereof.

In the drawings:

Figure 1, is a plan view of the locket open with the cover in cross section;

20 Figure 2, is a transverse sectional view through the closed locket, about on line 2—2 of Figure 1;

Figure 3, is a detailed sectional view on line 3—3 through the hinge; and

25 Figure 4, is a detailed perspective of the hinge plate and knuckle carried by the cover.

Referring more in detail to the accompanying drawing, the shell of the locket 30 comprises two complementary sections 1 and 2, the former constituting the bottom or body and the latter the top or cover therefor. The design of the locket is here depicted as being polygonal, although it can 35 be of other shapes. Within the body section 1 is fitted a flange 3 which is secured at spaced points, as by solder 4, and also by the carrying ring 5 whose shank is passed through perforations in the body wall and 40 the flange and then swaged as is clearly depicted in Figure 1. The ring 5 thus functions in a dual capacity in that it assists in securing the flange within the body wall as well as providing a means for attaching 45 a carrying chain or ribbon. The flange is pressed inwardly at one side to form a knuckle-receiving portion 6 and lateral bearings 7 which are closed by the body wall, the latter being cut away opposite the 50 portion 6, as indicated at 8.

A hinge plate 9 is secured against the inner wall of the cover section 2 and has a part 10 shaped to form a knuckle which operates in the cut out 8. The pintle or 55 pivot pin 11 is passed through the knuckle

10 and has its opposite ends mounted in the bearings 7.

By this construction the entire hinge is located within the inner wall of the sections, with the exception of a portion of 60 knuckle 10 which extends into the cut out. The hinge is well concealed within the body and does not project beyond the outer surface. The flange and cover may be formed with cooperating spring catch parts 12 adjacent the ring in an obvious manner.

Having thus described my invention, what I claim as new and desire to secure by Letters Patent is:—

1. A locket comprising a body and a 70 cover therefor, a flange fitted within the body so as to project above its edge and to be received by the cover when closed, said flange having a portion spaced from the adjacent wall portion of the body and 75 pressed to form a knuckle-receiving portion and lateral bearings, a knuckle carried by the cover, and a pivot pin passing through the knuckle and having its opposite ends engaged in the lateral bearings of 80 the flange where they are retained by the opposing adjacent wall portions of the body.

2. A locket comprising a body and a 85 cover therefor, a flange fitted within the body so as to project above its edge and to be received by the cover when closed, a carrying ring having a shank portion passed through perforations in the body and flange and serving to hold the latter in position, said flange having a portion spaced 90 from the adjacent wall portion of the body and pressed to form a knuckle-receiving portion and lateral bearings a knuckle carried by the cover, and a pivot pin passing through the knuckle and having its opposite ends engaged in the lateral bearings of 95 the flange where they are retained by the opposing adjacent wall portions of the body.

3. A locket comprising a shell formed of 100 complementary sections having meeting edges, a flange carried by one section so as to close the joint between the sections, a hinge knuckle carried by the companion section, and a hinge pin passed through the knuckle and having its opposite ends 105 secured between the flange and the adjacent wall portion of the flange-carrying section.

4. A locket comprising a shell formed of 110 complementary sections having meeting edges, a flange carried by one section so

as to close the joint between the sections, said flange having spaced bearings pressed inwardly from the wall of the section and closed thereby, a pivot mounted in the bearings, and a hinge carried by the companion section and engaging about the pin between the bearings.

In testimony whereof I have signed my name to this specification in the presence of two subscribing witnesses.

JOHN COSTELLO.
